SMOKING STAND AND ACCESSORIES
THEREFOREdward F. McDonald, Buffalo, N. Y., assignor to
Faries Manufacturing Company, Decatur, Ill.

Application November 23, 1931, Serial No. 576,922

6 Claims. (Cl. 131—51)

This invention relates to an article of furniture having especial utility for persons smoking tobacco.

It contemplates, generally, a slender upright portable standard which supports a carrying handle, a detachable waste receptacle, a torch, an electric ignitor for the torch, cigar or cigarette rests, all grouped together upon the standard. A fuel container and means for applying fuel to the torch are also provided and normally support the torch in the group of smoking utilities. Within the standard, preferably at the base thereof in order to stabilize the device, is disposed a source of electrical energy for the ignitor.

These and other objects and advantages of the invention including those residing in the formation and arrangement of the component parts of the device will become apparent from the following description of typical embodiments of the invention, reference being made to the accompanying drawings, wherein:

Fig. 1 is a perspective view depicting a complete smoker's stand constructed according to the principles of my invention;

Fig. 2 is a plan view of the device shown in Fig. 1;

Fig. 3 is a fragmentary vertical section, through an upper portion of the device, along line III—III of Fig. 2;

Fig. 4 is a central vertical sectional view through the complete device shown in Fig. 1;

Fig. 5 is a vertical sectional view taken along the line V—V of Fig. 2, depicting the ignitor elements in operative relationship;

Fig. 6 is a vertical sectional view taken at right angles to Fig. 5, along line VI—VI of Fig. 2;

Fig. 7 is a vertical fragmentary section taken on line VII—VII of Fig. 2;

Fig. 8 is a section taken on line VIII—VIII of Fig. 2;

Fig. 9 is a bottom plan view of certain parts depicted in Fig. 2;

Fig. 10 is a vertical section through the upper portion of a smoker's stand depicting modified means for supporting an ash or waste receptacle therein, the broken lines showing the receptacle parts detached from the supporting means;

Fig. 11 is a horizontal section taken along line XI—XI of Fig. 10;

Fig. 12 is a bottom plan view of the lower portion of the smoker's stand, illustrating the means which supply electrical energy to the ignitor elements and the manner in which the means are connected to the stand;

Fig. 13 is a perspective view of a bracket for

connecting the electrical energy supply means to the stand; and

Fig. 14 is a diagram showing the wiring connections of the smoker's stand.

As shown in Fig. 1, the smoker's stand comprises a slender upright standard 20, having enlarged base and head members 21 and 22 connected by a tubular member 23, having a top cover 24 supporting a group of smoking accessories or utilities including a torch 25 normally resting in a fuel container 26, an electric ignitor 27, cigar or cigarette rests 28, and an ash or waste receptacle having thereabove a lifting handle 29 adapted to lift the entire standard or, upon partial rotation, to lift the ash receptacle 15 from the standard.

A removable plate 31 closes the bottom of the tubular base member 21, the outer wall of which is engaged by an upwardly extending peripheral flange 32 of the plate. The head and base members are reduced to telescope within the connecting tube 23, as indicated at 33, and have inclined or semi-bayonet slots 34 for receiving bolts 35 extending through the tube 23. Annular beads 36 each having an inturned flange 37 engaged between the ends of the tube 23 and the shoulders 38 adjacent the reduced extremities 33 of the head and base, serve to conceal heads of bolts 35.

The cover plate 24 has a depending peripheral flange 39, for engaging the upper side wall portions of the head member 22, and has an opening 41 with a depressed wall 42 for seating an annular flange 43 of a funnel 44 which is thereby suspended within the standard 20. Laterally extending lugs 45 are provided on the funnel for engaging the depressed wall 42 of the cover plate, the wall having notches 46 with which the lugs 45 may be aligned upon partial rotation of the funnel by turning the handle 29 which is affixed thereto, to allow the funnel to be removed from or replaced within the standard. As shown in Fig. 9, a stop 47 on the wall 42 lies on the path of rotation of the lugs to limit the rotational movement of the funnel 44. To the latter is affixed, or joined in any suitable manner, a threaded cap 48 for receiving an ash or waste receptacle 49 having an upper end portion provided with complementary threads.

The cigar and cigarette rests 28, one or more of which may be provided, may be each affixed to the cover plate 24 by a bolt 50 embedded in the rest. As depicted in Figs. 7 and 8, the nut on bolt 49 secures an angle bracket 51 to the cover plate. The bracket 51 has a slot 52, parallel to the upper surface of the cover, for receiving the shank of a 55

stud 53 affixed to head member 21. It will thus be apparent that the cover is, in the position of parts shown in Figs. 7 and 8, positively retained on the standard head, and that it may be removed therefrom by partial rotation to release the studs 53 from the slots 52.

The portable torch 25, comprises a handle 54 and a torch portion 55 consisting preferably of rings of asbestos or like substance mounted upon a stem 56, being retained thereon by a shoulder 57 and a retaining nut 58 at the lower end of the stem. The upper end of the stem is preferably threaded into the handle and is reduced to provide a shoulder 59 for retaining a convex sealing ring 60. A shield 62 is clamped between the sealing ring and handle. Normally the torch is supported in a fuel container which includes a jar 63 having a threaded cover 64 and a sealing gasket 65. The fuel container extends through an opening 66 in the cover plate 24 of the standard, notches 67 being provided about the opening for passing fingers 68 on a plate 69 which normally engage under the cover plate 24 to retain the fuel container against removal. A supporting plate 71 seats upon the cover plate 24 and preferably extends above the latter a distance equal to the height of the ignitor element 27.

The supporting plate 71 is clamped to the plate 69 and cover 64 by a torch supporting tube 72 having a shoulder engaging the upper surface of the supporting plate and a wick supporting tube 73 abutting the lower surface of the jar cover 64, tube 73 being threaded to the torch supporting tube. The wick tube 73 is restricted at its lower end to retain felt, or other suitable wick material, 74, openings 75 in the tube permitting fuel from the jar 63 to infiltrate the wick. As shown in Fig. 3, the torch portion 55 is normally disposed in and contacts the walls of a recess in the wick. The upper end of the torch tube 72 is convex so as to contact on a continuous line with the sealing ring 60 of the torch, to provide a gas-tight seal between the torch and fuel container regardless of the angular disposition that the stem 56 may assume in engaging the recess within the wick.

The ignitor 27 comprises a base 76 of insulating material and has a flange 77 extending through an opening in the cover plate 24 and overlying the cover plate 24. The latter supports a strap 78 through which bolts 79, embedded in base 76, extend. An electric contact finger 81 is supported by one of the bolts, being electrically insulated therefrom and from the strap 78 by washers 82.

The base 76 has a funnel shaped well 83, the bottom of which is shouldered at 84 to confine a movable contact member 85, the stem 86 of which is slidable in the guide aperture of the strap 78. A spring 87, extending about the stem 86, normally urges the contact member against shoulder 84, out of contact with finger 81. An electric lead wire 88, connected to finger 81, extends to one terminal, 89, of a battery 91 disposed within the base 21. The opposite terminal, 92, of the battery is connected by wire 93 to one terminal, 94, of the primary winding of an induction coil 95, including a circuit interrupter 96, the other terminal, 97, of primary winding of the induction coil being joined to one terminal of the secondary winding and grounded to the standard, thus being in electrical circuit through the standard, top cover 24 and strap 78, with the movable contact member 85. The other terminal 98 of the secondary winding of the induction coil is

connected by wire 99 to a spark button 101 disposed on the diverging side walls at the top of the well in the ignitor base.

The battery and induction coil are supported in the base 21 of the standard by the bracket, depicted in Fig. 13, which includes a strap 102 having ends 103 and 104 apertured for the reception of bolts 105 which secure the bracket to angles 106 anchored to the base. A portion, 107, of strap 102, is formed to substantially 10 U-shape to provide a saddle for receiving the battery 91 and for supporting a generally U-shaped strap 108, which carries binding posts 109 adapted to contact the terminals of the battery, these preferably comprising springs. 15 Flanges 110 and 111, respectively, engage and give lateral support to the battery and the induction coil. A third bracket section, 112, of generally L-shape, extends from one leg of the U-shaped portion 107 of strap 102 to the end 20 104 thereof, to embrace and retain in place the induction coil. Member 112 supports an insulating bar 113 which carries a binding post 114 in contact with terminal 98 of the secondary winding, and a contact member 115 for contacting the joint primary and secondary terminal 97. A metal strip 116 serves to ground the later terminal to the bracket.

In use the device for lighting a cigar, cigarette, pipe, or the like, the torch with its torch portion 55 saturated with fuel, from the container 63 and wick 74, such as alcohol or other readily ignitable hydro-carbon, or hydro-carbon derivative, may be withdrawn from the supporting tube 72 and inserted in the well of the ignitor base, as shown in Fig. 5, to depress the movable member 85 into contact with finger 81. This will complete an electrical circuit through the battery and primary winding of the induction coil which may be traced as follows: terminal 89 of the 35 battery, wire 88, finger 81, contact member 85, strap 78, the standard, the battery bracket, strip 116, terminal 113, the primary winding of the induction coil (including the circuit breaker), terminal 94, and wire 93 to the other terminal 92 of the battery. 45

A circuit having induced current of high voltage will simultaneously be created, the induced current arcing between the spark button 101 and the portion of stem 56 of the torch which is covered by or is adjacent to the fuel saturated torch portion 55. The induced current circuit may be traced as follows: from the secondary winding of the induction coil, terminal 113, the battery bracket, the standard, strap 78, movable contact 85, stem 56 of the torch, through the air to button 101 and wire 99 to terminal 98 of the secondary winding. The fuel on the torch will be ignited by the electric spark or arc, so that the torch may be used to light a cigar, cigarette, pipe, or for other purpose. Upon replacement of the torch within the tube 72, the flame will be immediately extinguished and the supply of fuel on the torch portion 69 will be replenished.

Ashes and other waste placed in funnel 44 will be discharged into the container 49. The restricted opening at the lower end of the funnel will be effective to prevent smoke or fumes from arising from the container. The latter may be 65 emptied by turning handle 29 to bring the lugs 45 of the funnel into registry with notches 46 in the cover and then, by the handle 29, withdrawing the funnel and the attached container 49, the latter being removable from the funnel by turn- 75

ing it. When the waste receptacle is in normal position, the handle 29 may be used to lift the entire smoker's stand.

The fuel container may be refilled by extracting it from the standard, after partial rotation to bring fingers 68 into registry with the notches 67 in the cover plate 24, and by then unscrewing the jar 63 from its cover 64. Normally a struck out stop 60 on the plate 24 (shown in Fig. 9) limits the rotational movement of the fuel container. The battery is likewise readily removed for replacement, this being accomplished by removing the bottom closure 32 from the standard and lifting the battery from its supporting bracket. When positioned as shown in Fig. 12, the spring terminals 89, 92 of battery 91 hold it clamped between the binding posts 109 and the flange 110 on the U-shaped strap 108.

In the construction depicted in Figs. 10 and 11, the standard 20, including the head member 22, tube 23, and cover 24 are the same as those shown in Figs. 3 and 4, the cover plate having a depending flange 39 and a depressed portion 42 about the central opening 41. A funnel 44' is provided which has an annular flange 43, seated on the depressed portion 42 of the cover plate, and which has a handle 29' affixed thereto. Lugs 45', secured to the funnel, engage under the portion 42 to normally retain the funnel in place. Secured to the lower reduced end of the funnel is a shallow annular cup 48' for receiving and providing a closure for a waste or ash receptacle 49'. The base of the latter is received in a cup 120 which has a pair of guide tongues 121 struck out on each side thereof for slidably engaging the leg portions of a generally U-shaped strap 122.

Strap 122 is rigidified adjacent its upper end by a band 123 which encircles and may guide the receptacle 49'. The upper extremities 124 of the legs of the U-strap 122 extend in adjacency with the under surface of the plate 24 and are secured thereto by the bolts 50 which secure the cigar rests 28. The end formation and the function of the portions 124 of strap 122 are substantially the same as those of angle brackets 51, each portion 124 having a slot 125 to slidably receive a stud 53 affixed to the head section 22 of the standard.

A coil spring 126 secured to the base 127 of the strap 122 and to the cup 120, normally urges the latter upwardly to press the receptacle 49' into contact with the annular cup 48'. When it is desired to empty or clean the receptacle 49', the handle 29' may be partially rotated to align the lugs 45' with notches 46 in the cover plate, whereupon the spring 126 will lift the receptacle to the broken line position of Fig. 10. The funnel may then be lifted away and the receptacle removed from the standard.

It will be understood that when the device is to be used at places where an alternating current supply, such as that ordinarily provided in homes and offices, is available, a step-up transformer may be substituted for the battery and induction coil shown in Fig. 12.

It will be further understood that the devices herein described and illustrated are merely exemplary of the principles of the invention, which may be embodied in other devices having other structural characteristics and arrangements, all

within the purview of the invention as set forth in the claims.

What is claimed is:

1. A receptacle for a smoking stand, comprising a funnel having an enlarged mouth and a restricted discharge opening, a peripheral flange about said enlarged mouth, a detent protuberance spaced from said flange, a waste container, a cap releasably secured to said waste container and joined to said funnel adjacent the discharge opening, and a handle secured to and extending across the mouth of said funnel.

2. In a smoking stand, an upright tubular standard, a cover plate therefor, a stud extending from a wall of said standard adjacent to the cover, a smoking accessory on said cover plate, and a bracket beneath said cover plate having an open mouthed slot receiving said stud, said slot extending in a plane substantially parallel to the plane of said cover plate, and fastening means connecting said stud bracket and accessory to said cover plate.

3. In a smoking standard, a pair of tubular members, one of said members having an annular shoulder adjacent the end of the other member, the first mentioned one of said members having a reduced portion joining said shoulder and telescoped within the second mentioned member, one of said members having an inclined slot at the end thereof and the other of said members carrying a fastener engaged in said slot, and an annular member about the telescoped portions and having an inturned flange seated between said shoulder and the end of the second mentioned member.

4. In a smoking stand, or the like, a tubular standard, a cover plate therefor having an opening therein, a stud extending from a wall of said standard adjacent the cover, a member secured to said cover and having end portions slotted to receive said stud, the central portion of said member being of substantially U-shape, a cup extending across and guided by the upright portions of said U-shaped portion, a spring between the base of the U-shaped portion and the cup for urging the latter upwardly, a waste container seated in the cup, and a funnel extending through said opening in the cover plate and abutting said waste container, and means releasably securing the funnel to the cover plate, whereby upon release of said means said spring will move the cup upwardly and cause the waste receptacle to extend through said opening in the cover.

5. In a smoking stand, or the like, an upper member having an opening therein, a waste container depending from said member in alignment with said opening, releasable means for restraining upward movement of said container through said opening, resilient means for urging upward movement of the container, and guide means for guiding the container through the opening when said first mentioned means are released.

6. In a smoking stand, or the like, a supporting plate having an opening therein, a funnel extending through said opening and releasably secured to said plate, a waste receptacle beneath said funnel and in contact therewith, and spring means beneath said receptacle and carried by said plate for urging the receptacle upwardly into said opening upon release of the funnel from the plate.

EDWARD F. McDONALD.
